UNITED STATES PATENT OFFICE.

ALEXANDER J. GUTTMAN AND JACOB R. AIMS, OF NEW YORK, N. Y.

DESIGN FOR A PUZZLE-BOARD.

SPECIFICATION forming part of Design No. 35,160, dated October 1, 1901.

Application filed July 31, 1901. Serial No. 70,434. Term of patent 3½ years.

To all whom it may concern:

Be it known that we, ALEXANDER J. GUTTMAN and JACOB R. AIMS, citizens of the United States, and residents of the city of New York, 5 borough of Manhattan, in the county and State of New York, have invented and produced a new and original Design for a Puzzle-Board, of which the following is a full, clear, and exact description.

Reference is to be had to the accompanying drawings, forming a part of this specification, in which similar characters of reference indicate corresponding parts in both views.

Figure 1 is a plan view of the puzzle-board, 15 showing our design; and Fig. 2 is a sectional side elevation of the same on the line 2 2 in Fig. 1.

The design in its entirety consists of a pan-shaped receptacle A, having a handle B con- 20 caved and enlarged at its outer end B', the latter appearing with the representation of a buffalo's head in relief and the receptacle ap-

pearing in its bottom with a central depression D and ribs E, radiating from the depression and terminating a distance from the rim 25 of the receptacle.

The main feature of the design consists of the pan-shaped receptacle E, appearing at its bottom with a central depression and ribs ex- 30 tending therefrom.

Having thus described our invention, we claim as new and desire to secure by Letters Patent—

The design for a puzzle-board herein shown and described.

In testimony whereof we have signed our names to this specification in the presence of two subscribing witnesses.

ALEXANDER J. GUTTMAN.
JACOB R. AIMS.
